UNITED STATES PATENT OFFICE.

CHARLES H. BROCKWAY, OF DETROIT, MICHIGAN.

VALVE-LIFTER.

1,247,366.

Specification of Letters Patent. Patented Nov. 20, 1917.

Application filed March 9, 1917. Serial No. 153,807.

To all whom it may concern:

Be it known that I, CHARLES H. BROCKWAY, a citizen of the United States, residing at Detroit, in the county of Wayne and State of Michigan, have invented a certain new and useful Improvement in Valve-Lifters, of which the following is a full, clear, and exact description, reference being had to the accompanying drawings.

10 This invention relates to an improved valve lifter or tappet for use with internal combustion engines, and it has for its main object the economical production of an extremely light device of this character.

15 Valve tappets or lifters have heretofore been turned from a solid bar of stock, with a consequential waste of material and the production of an unnecessarily heavy article. It is essential that the cam engaging 20 face of the lifter be hardened in order to resist the wear to which it is subjected, and in these turned types of lifters the entire article has to undergo the hardening process with the liability of warping the parts of 25 the tappet out of proper relation to each other, and the loss of the entire article, should the process fail.

My invention provides for the making of the body portion of the tappet or lifter of 30 sheet metal, drawing or otherwise shaping it into a hollow barrel and head, and into the latter the insertion of a hardened steel disk which may be secured in place preferably by turning the periphery of the head 35 over the edge of the disk. A pad or gasket of some suitable comparatively soft material, such as lead, may be inserted between the disk and head to cushion the action of the disk against the head, and in the event 40 that there is play between the parts, and to deaden the sound resulting from the action of the cam upon the tappet.

A further object comprehended by my invention is the provision of a very simple and 45 effectual means of adjustment to compensate for any shortening, as by wear, of the parts between the cam and valve.

The foregoing objects are attained in the very simply constructed tappet illustrated 50 in the drawing accompanying and forming a part hereof wherein Figure 1 is a sectional detail through the crank case of an engine showing my improved tappet in elevation interposed between a cam and valve rod; 55 Fig. 2 is a central vertical section through the tappet; Fig. 3 shows, in perspective, the

parts of the tappet in separated condition, the body portion of the tappet being in section; and Figs. 4 and 5 illustrate the adaptability of prevailing adjustments, to my 60 improved tappet or lifter.

To portray the environments of my invention I have shown a sectional detail through a common engine construction wherein 1 represents a crank case having an 65 aperture 2 in its top wall through which projects the lower end of a guide 3, in axial alignment with which is the valve stem 4 above and the cam 5 below.

As previously stated, the body portion of 70 the tappet is formed of a single piece of sheet metal and comprises a barrel 10 and head 11. The periphery of the head is turned over in a direction away from the barrel to produce a flange 12. The larger 75 diameter of a beveled edge disk 15 is adapted to be inserted within the cavity of the head 11 and to be held therein by the inwardly pressed edge of the flange 12. Prior to assembling, the disk 15 is hardened for the 80 purpose already explained. A pad 16, which may be in the form of a disk or washer, and consisting of some comparatively soft material, such as lead, may be inserted between the disk and the inner surface of the 85 head, although the use of this pad is not deemed absolutely necessary. It serves to dampen the noise produced by the action of the cam upon the disk 15, especially if the disk, or any portion of it, should be 90 loose.

The upper end of the barrel 10 may be inset, as shown at 17, to receive therewithin plates or shims 20 through which an adjustment is accomplished by the inclusion of the 95 required number of shims to compensate for any wear of the parts that would result in a shortening of the distance between the cam and valve. The upper end of the barrel may be notched on each side to substantially 100 the depth of the shim cavity, as indicated at 21, to facilitate the insertion or removal of the shims, and to enable the number of shims employed to be readily ascertained.

Instead of the method of adjustment just 105 described, I may employ a very common expedient in the form of an adjustment screw 25 shown in Fig. 4, as threaded within the reduced and internally threaded upper end of the barrel 10. Or I may adopt a more 110 recent practice and apply a cap 28 to the end of the barrel, said cap having prongs

29 stuck out of its circular wall and bent upward to receive between them the shims 30.

From the foregoing description it will be seen that my invention provides for a very cheap and convenient production of a highly efficient tappet that is extremely light, and that requires the hardening of only the disks 15 in order to make its wearing qualities equal to those of its more expensive and prohibitively heavy predecessor.

Having thus described my invention, what I claim is:

1. As a new article of manufacture, a tappet comprising a barrel formed of sheet metal and having a valve operating end, and a cam engaging element attached to its opposite end.

2. As a new article of manufacture, a tappet comprising a barrel formed of sheet metal, a cam engaging element attached thereto, and a shock absorbing member interposed between the element and barrel.

3. As a new article of manufacture, a tappet comprising a sheet metal barrel having a flared end, and a cam engaging element of hardened material attached to said flared end.

4. As a new article of manufacture, a tappet comprising a sheet metal barrel having a flared end, a cam engaging element attached to said flared end, and a shock absorbing pad interposed between the element and said end.

5. As a new article of manufacture, a tappet comprising a sheet metal barrel having its end flared outward into a plane perpendicular to the axis of the barrel, a cam engaging disk applied to said portion and held in place by the turned over edge of said portion.

6. As a new article of manufacture, a tappet comprising a sheet metal barrel having its end flared outward into a plane perpendicular to the axis of the barrel, a cam en-

gaging disk applied to said portion and held in place by the interlocked edges of said portion and disk.

7. As a new article of manufacture, a tappet comprising a sheet metal barrel having its lower end flared outward and then flanged downward to produce a recessed head and a disk held within the recess of the head by the downwardly flanged portion.

8. As a new article of manufacture, a tappet comprising a sheet metal barrel having its lower end flared outward and then flanged downward to produce a recessed head, and a beveled edge disk having its side of greater diameter retained within the recess of the head by the downwardly flanged portion thereof.

9. As a new article of manufacture, a tappet comprising a sheet metal barrel having its lower end flared outward and then flanged downward to produce a recessed head, a disk held within the recess of the head by the downwardly flanged portion thereof, and a shock absorbing pad interposed between the disk and head.

10. As a new article of manufacture, a tappet comprising a sheet metal barrel having an abutment inset from one end for the support of adjustment shims, and a cam engaging element attached to the opposite end of said barrel.

11. As a new article of manufacture, a tappet comprising a sheet metal barrel having a closed inset end for the reception of adjustment shims, and a cam engaging element attached to the opposite end of said barrel.

In testimony whereof, I hereunto affix my signature in the presence of two witnesses.

CHARLES H. BROCKWAY.
